Attorneys

UNITED STATES PATENT OFFICE.

JOSEPH N. KELMAN, OF LOS ANGELES, CALIFORNIA.

OIL CIRCUIT BREAKER.

Application filed November 28, 1921. Serial No. 518,130.

To all whom it may concern:

Be it known that I, JOSEPH N. KELMAN, a citizen of the United States, residing at Los Angeles, in the county of Los Angeles and 5 State of California, have invented a new and useful Improvement in Oil Circuit Breakers, of which the following is a specification.

My invention relates to oil circuit breakers, such as are commonly used in power systems, for opening the circuit of high tension transmission lines.

It is a well known fact that the disturbances produced in opening circuits of 50,000 volts and over, where there is large generating capacity connected to the line, are often 15 very serious. It is also a well known fact that many of the ordinary types of oil circuit breakers have considerable difficulty in opening such lines, due to the tendency of 20 the circuit to persist, and for arcs to persist between the contacts during the opening period. This results in injury to the circuit breaker, due not only to the burning effect of the arc, but also to the explosive effect of 25 the gases generated, which may injure the tanks of the circuit breaker, or it may throw oil or hot gases from the circuit breaker tank with injury to the attendants, or adjoining apparatus.

30 The principal object of my invention is to provide an oil circuit breaker which will promptly extinguish any arcs formed in the circuit breaker, and which will utilize the explosive force of one of these arcs to extinguish succeeding arcs.

Further objects and advantages will be made evident hereinafter.

Referring to the drawing, which is for illustrative purposes only,

40 Fig. 1 is a plan view of a three pole circuit breaker embodying my invention, the top and mechanism being removed from the right hand tank to better illustrate the interior structure.

45 Fig. 2 is an elevation, a portion of the right hand tank being shown in section to better illustrate the interior structure.

Fig. 3 is a partial section on a plane, represented by the line 3—3, Fig. 2, and

50 Fig. 4 is a view of the contacts in their open position.

In the form of the invention illustrated, there is shown a three pole circuit breaker, which is adapted to open the three phases 55 of an ordinary transmission line. Each pole of the circuit breaker consists of a tank 11

having two high tension bushings 12 which extend through a tight top 13 secured on the tank 11. An operating shaft 15 extends through all three of the tanks 11, being operated by suitable mechanism 16, which is standard in the art and forms no part of the present invention.

Secured to the shaft 15, inside each of the tanks 11 are three cranks 20 to each of which 60 is pivoted a connecting rod 21, which is secured on an insulator 22. The insulator 22 carries at its lower end a clevis 23 to which moving blades 24 are secured, these blades being guided by links 25, secured to a central insulator 26. There are three of these cranks 20, and three sets of the mechanism members 20 to 26, in each of the tanks. The blades 25 make contact with stationary jaws 31, 32, 33, 34, 35 and 36, each carried on an 70 insulator 30. It will be seen that the first set of blades 24 connect between the jaw 31 and the jaw 34, and that the second set of blades connect the jaw 32 with the jaw 35, and that the third set of blades connects the 75 jaw 33 with the jaw 36. A conductor 40 passes through one of the high tension bushings, and a conductor 41 passes through the other. The conductor 40 is connected through a wire 42, with the jaw 33, and the 80 conductor 41 is connected through a wire 43 with the jaw 34. The jaws on the insulators 31 and 32 are connected together by a wire 55 and the jaws on the insulators 35 and 36 are connected together by a wire 56. 90

With the switch closed, a circuit is established from the conductor 41, through the wire 43 to the jaw 34 across the first set of blades 24 to the jaw 31, through the wire 55 to the jaw 32, through the second set of 95 blades 24 to the jaw 35, through the wire 56 to the jaw 36, and through the third set of blades to the jaw 33, and through the wire 42 to the conductor 40.

When it is desired to open the circuit, the 100 shaft 15 is rotated in a counter clock-wise direction, as shown in Fig. 3, pulling upwardly on all three of the connecting rods 21 and raising each of the clevises 23. This pulls upwardly on the inner ends of the 105 blades 24 pulling them from the position, shown in Fig. 3, into the position shown in Fig. 4. This opens the circuit of each of the jaws making in all six breaks in each phase of the circuit.

110 Situated between the jaws 31 and 33, 34 and 36 are tubes 60 which are formed of

insulating material, and which are provided with suitably formed slots 61 to permit the placing of the tubes 60 over the centrally disposed jaws 32 and 35, and to allow the engagement of the central blades 24 therewith as shown in Fig. 3. The blades 24, entering the jaws 32 and 35, are arranged to open the circuit before any of the other blades open the circuit. As a result, the initial breaking of the circuit takes place at the central jaws 32 and 35, within the tubes 60. If the circuit is heavily overloaded, as generally occurs when these circuit breakers are called upon to act, there is a great tendency of an arc to form at these contacts and this arc tends to vaporize the oil and to cause an expansion or explosion. This explosion, acting in all directions, forces oil to flow at a very high velocity through the tubes 60, the ends of these tubes being immediately adjacent to the other jaws, which open soon after the central jaws have opened. At the instant the outer jaws open, however, there is a very strong jet of oil moving across the space, immediately inside these jaws, this high velocity jet of oil tending to immediately wipe out or disperse any arcs which form on the outer jaws.

My invention is new and basic, in that I use the force of an explosion produced at the central jaws to prevent a persistence of any arc formed at the outer jaws. Since the breaks are all in series in any tank, it is evident that although the arc may persist at the central contact for a short space of time, yet the greater the force of this arc, the less likelihood there is of an arc persisting between the outer jaws and their corresponding blades, and the more likelihood there is of the circuit being opened at one or more of these points.

I claim as my invention:

1. In an oil circuit breaker, the combination of: a tank in which the oil is carried; a plurality of sets of contacts in said tank, each set being adapted to interrupt the circuit; and directional means by which the expansion due to opening the circuit at one of said sets of contacts forcing oil in the direction of another set of said contacts.
2. In an oil circuit breaker, the combination of: a tank in which the oil is carried; a plurality of sets of contacts in said tank, each set being adapted to interrupt the circuit; and an oil director so placed that the force of any explosion between one set of contacts forces oil in the direction of another set of contacts.

3. In an oil circuit breaker, the combination of: a tank in which the oil is carried; 60 a plurality of sets of contacts in said tank, each set being adapted to interrupt the circuit; and a tube situated between two of said sets of contacts and so placed that a sudden expansion of the oil at one end of 65 said tube causes oil to flow toward one of said sets of contacts.

4. In an oil circuit breaker, the combination of: a tank in which the oil is carried; 70 a plurality of sets of contacts in said tank, each set being adapted to interrupt the circuit; means for opening one of said sets of contacts in advance of the others; and means for using the expansion produced by the opening of said set to extinguish an arc on 75 a set opening thereafter.

5. In an oil circuit breaker, the combination of: a tank in which the oil is carried; 80 a plurality of sets of contacts in said tank, each set being adapted to interrupt the circuit; means for opening one of said sets of contacts in advance of the other; and a directional means for utilizing the expansion produced by said opening set to force oil in 85 the direction of the other set.

6. In an oil circuit breaker, the combination of: a tank in which the oil is carried; a plurality of sets of contacts in said tank, each set being adapted to interrupt the circuit; means for opening one of said sets of 90 contacts in advance of the others; and an oil director so placed as to direct oil moving from said first opening set toward another one of said sets.

7. In an oil circuit breaker, the combination of: a tank in which the oil is carried; a plurality of sets of contacts in said tank, each set being adapted to interrupt the circuit; means for opening one of said sets of contacts in advance of the others; and a tube 100 having one open end adjacent to said first opening set and the other open end directed toward another one of said sets.

8. In an oil circuit breaker, the combination of: a tank in which the oil is carried; 105 a plurality of sets of contacts in said tank, each set being adapted to interrupt the circuit; means for opening one of said sets of contacts in advance of the others; and a tube substantially enclosing the first opening of 110 said sets having its ends directing toward the other of said sets.

In testimony whereof, I have hereunto set my hand at Los Angeles, California, this 21st day of November, 1921.

JOSEPH N. KELMAN.
